UNITED STATES PATENT OFFICE

BERT E. BARTHOLOMEW, OF SANTA ANA, CALIFORNIA, ASSIGNOR TO CONSOLIDATED FACTORIES LIMITED, OF SANTA ANA, CALIFORNIA, A CORPORATION OF CALIFORNIA

WINDOW PULLEY

Application filed November 6, 1929. Serial No. 405,110.

This invention relates to improvements in window supporting pulleys.

The general object of this invention is to provide an improved window pulley construction particularly designed for use with a double window and wherein the upper and lower sections are secured to opposite ends of the same cords.

Another object of the invention is to provide a window pulley construction which may be either used below or above the top frame of the window.

Other objects and the advantage of this invention will be apparent from the following description taken in connection with the accompanying drawings wherein:

Fig. 1 is a face view of a window embodying the features of my invention with the front window frame plates removed and with various parts in section to more clearly illustrate the invention.

Fig. 2 is a section taken on line 2—2 of Fig. 1.

Fig. 3 is a section taken on line 3—3 of Fig. 1.

Fig. 4 is a section similar to Fig. 2 showing the upper window closed.

Fig. 5 is an enlarged face view of one of my improved pulley devices.

Fig. 6 is an end view of the pulley shown in Fig. 5.

Fig. 7 is a section taken on line 7—7 of Fig. 5 and showing the cord.

Fig. 8 is a section taken on line 8—8 of Fig. 5.

Fig. 9 is a section taken on line 9—9 of Fig. 7.

Fig. 10 is a bottom plan view of the device.

Fig. 11 is a top plan view of the device.

Fig. 12 is a view similar to Fig. 2 showing the pulley device positioned above the top window frame and

Fig. 13 is a sectional view of the device when positioned above the top window frame.

Referring to the drawings by reference characters I have indicated my improved pulley devices generally at 10. As shown this device includes a case 12 and a cover

plate 13. The case 12 includes sides 14 having at one end thereof ears 15 which are provided with apertures 16 and top and bottom members 17 and 18. In the top member 17 there are provided a pair of spaced apertures 19 and in the bottom member 18 a pair of spaced apertures 20 are provided.

The cover plate 13 includes a top member 21 and a bottom member 22 which is cut off adjacent each side as indicated at 23 to allow an unobstructed passage through the apertures 20 of the case while the top member 21 extends the full width and obstructs the passage through the apertures 19 in the top member 21 of the case.

The cover plate 13 and case 12 are shown as adapted to be secured together by a bolt 24 and a nut 25 and the bolt 24 is adapted to act as a shaft on which is rotatably positioned a grooved pulley 26.

The nut 25 is preferably soldered, welded or otherwise secured to the cover whereby the bolt 24 may be removed without disturbing the nut.

My improved pulley mechanism 10 may be either mounted below the upper frame member 27 of the window as shown in Figs. 1 to 4 inclusive or it may be mounted above the upper frame member of the window as shown in Figs. 12 and 13.

When a pair of the devices 10 are mounted as shown in Figs. 1 to 4 inclusive they are adapted to be secured to the under side of the upper frame member 27 of the window by a plurality of screws 28 and the devices 10 are preferably positioned so that the cover plates 13 face inwardly whereby they may be readily removed to allow access to the interior of the devices upon removal of the bolts 24.

Positioned over each of the pulleys 26 there is provided a cord 29 one end of which may be secured to one closure member 30 and the opposite end of which may be secured to another closure member 31.

When the devices 10 are positioned below the upper frame member 27 of the window the closure members 30 and 31 are provided with recesses 32 in the upper portions thereof to provide clearance for the devices 10.

when either one of the closure members are moved upward as shown in Fig. 4.

When the devices 10 are positioned above the upper frame member 27 of the window

5 as shown in Fig. 12 the cover plate 13 is positioned in the case 12 so that the member 21 of the cover closes the apertures 20 of the case and the short cover and member 22 allow a free passageway through the apertures 19 of the case 12 as shown in Fig. 13.

10 When the devices 10 are thus positioned above the frame member 27, apertures 33 are provided in the frame member adjacent the apertures 19 of the devices 10 in which the cords 29 are adapted to be positioned.

15 From the foregoing description it will be apparent that I have provided a novel window closure supporting pulley device which is extremely simple in construction yet highly efficient in use.

20 Having thus described my invention what I claim is:

25 1. In a device of the class described, a case, said case including a back, side members and end members, an aperture in said end members adjacent each side thereof, a cover for said case, said cover including means adapted to allow free passageway through the apertures at one end of said case and means adapted to obstruct the passageway through the end apertures at the opposite end of said case, means to secure said cover to said case, and a pulley rotatably supported in said case.

30 35 2. In a device of the class described, a case including end members, an aperture in each end member adjacent each side thereof, a cover for said case, said cover including end members, one of said end members terminating short of the sides of said cover, said short end member of said cover being arranged to allow free passageway through the apertures at one end of said case and said long cover end member being adapted 40 45 to obstruct the passageway through the apertures at the opposite end of said case, a pulley and means to rotatably support said pulley in said case.

50 55 3. In a device of the class described, a case, said case including a back, side members and end members, outwardly extending tongues on said side members adjacent one end thereof, an aperture in said end members adjacent each side thereof, a cover for said case, said cover including a back and end members, one of said end members extending the full width of said back and the other of said end members terminating short of the sides of said cover, said 60 65 cover being adapted to be positioned on said case with the back thereof spaced from said case back and with the end members thereof positioned inwardly of said case end members, said long cover end member being arranged to obstruct the passageway

through the apertures at one opposite end of said case, means to secure said cover to said case and a pulley, positioned in said case.

4. In a device of the class described, a 70 member including a back, sides and ends, there being an aperture in said ends adjacent each side thereof and a cover for said member, said cover including means adapted to allow free passageway through the apertures at one end of said member and means adapted to obstruct the passageway through the end apertures at the opposite end of said case, means to secure said cover to said case, and a pulley rotatably supported in said 75 80 case.

In testimony whereof, I hereunto affix my signature.

BERT E. BARTHOLOMEW.
